UNITED STATES PATENT OFFICE.

DANIEL MANSON SUTHERLAND AND DANIEL MANSON SUTHERLAND, JR., OF SUNBURY COMMON, ENGLAND.

APPARATUS FOR THE MANUFACTURE OF SHEETS OF PULP.

971,936.

Specification of Letters Patent.

Patented Oct. 4, 1910.

Application filed October 19, 1908. Serial No. 458,371.

To all whom it may concern:

Be it known that we, DANIEL MANSON SUTHERLAND and DANIEL MANSON SUTHERLAND, Jr., both subjects of the King of Great Britain, residing, respectively, at 5 Ashgrove, Sunbury Common, in the county of Middlesex, England, managing director, and St. Helens, Nursery Road, Sunbury Common aforesaid, assistant manager, have 10 jointly invented certain new and useful Apparatus for the Manufacture of Sheets of Pulp, Wood-Pulp, or the Like, of which the following is a specification.

Thick, large sheets of paper pulp, wood 15 pulp or the like, are made by running the pulp into a mold consisting of a lower frame holding a sheet of wire gauze or the like forming the bottom of the mold, an upper frame holding a similar sheet constituting 20 the top of the mold and a frame or separate boards constituting the sides of the mold and called a deckle. The pulp having been filled into the mold the upper frame is laid in place and pressed to expel the liquid from 25 the pulp. The bulk of the liquid passes through the bottom of the mold, but some always passes upward through the top and before the top frame can be removed for the purpose of removing the sheet the whole 30 mold must be tipped in order to drain away this water. The mold is then laid horizontally, the top frame and the deckle are removed and the bottom frame is turned over and allowed to fall on to the trolley or the 35 like that is to receive the sheet in order that the latter may be detached from the wire cloth. These manipulations are laborious and occupy time and the shock of the fall damages both the frame and the sheet. In 40 another mode of manufacturing articles from wood pulp, while pressure is applied to the mold, a vacuum is made above the top of the upper mold frame and maintained so as to cause the article to adhere to that 45 frame when the upper and lower frames are taken apart, then, when it is desired to detach the article, the vacuum is destroyed and the article by means of compressed air is blown off the frame on to a device located 50 below the upper frame and adapted to remove the article from between the two frames. Now according to the present invention, while the vacuum is maintained above the top frame, this frame together 55 with an adhering sheet of pulp is moved in

a direction laterally to that of the pressure; in other words from above the lower frame, until it is exterior to the molding apparatus and is brought to a desired position, it may be over a trolley or the like, the vacuum is 60 destroyed in order to allow the sheet to fall upon the bed by its own weight and through a distance as small as may be desired. With suitable arrangements the suction applied above the top of the mold may serve to remove the portion of liquid which, as aforesaid, is expelled upward. Preferably, the mold is placed in a press, the lower table 65 of which can be raised or lowered such as by hydraulic power. The upper frame of 70 the mold is fitted to a suction box arranged to drain or suck away water and air. The upper frame together with its suction box may be mounted on wheels running on rails to permit the prepared sheet, after the lower 75 frame has been lowered, to be conveyed to the required position over the trolley or the like. The combination of the pressure on the lower frame and suction on the upper accelerates the extraction of the liquid from 80 the pulp and makes a better sheet, in addition to facilitating the couching of the sheet as aforesaid.

In the accompanying drawings, Figure 1 is a front elevation of the apparatus for 85 applying the invention, showing the upper frame and suction box in position vertically over the lower frame; Fig. 2 is a similar view showing the upper frame and suction box shifted laterally from the position in 90 Fig. 1 to a position over the conveyer or trolley; and Fig. 3 is one section on the line III—III of Fig. 1, having certain parts removed.

A is the platen, and B the head of a hy- 95 draulic press P.

C is the bottom frame of the mold and D is the deckle.

E is the top frame of the mold and is at- 100 tached to the suction box F.

H is a main suitably connected with a suitable exhaust pump H', for instance by a swiveling swing pipe H² and H³ provided with a stop cock H⁴.

Branch ducts on pipes L from this main 105 extend into the suction box and from this branch other branches or ducts M extend downward to the wire gauze of the top frame.

Fig. 2 shows the suction box F, suitably 110

mounted on wheels and adapted to be shifted laterally along rails O suitably carried by the press P and supported on supports Q, not here shown, to a place exterior to the 5 press it may be above the trolley J where the vacuum in box F is destroyed, and the sheet G allowed to fall upon the previously made sheets K.

By suitably connecting the main H with a 10 supply of compressed air during the period when pressure is being applied to the mold, the pressure within the suction box may be suitably increased to prevent any water from entering the box. One way of connecting 15 the main with the compressed air source is shown in Fig. 1 where the pump H⁵ is connected to the swing pipe H² by means of pipe H⁶ having a stop cock H⁷.

Having thus described the nature of this 20 invention and the best means we know of carrying the same into practical effect, we claim:—

1. In apparatus for the manufacture of thick large sheets of paper pulp, wood pulp 25 or the like, the combination of a press, a lower mold part adapted to contain pulp and fitted to the press, a movable upper mold part detached from the press normally mounted above the lower mold part and 30 adapted to coöperate therewith, a suction box attached to the upper mold part, means for pressing said mold parts together to form a sheet, and means whereby the upper mold part, the sheet and the suction box 35 may be moved from above the lower mold part to a position external to the press.

2. In apparatus for the manufacture of thick large sheets of paper pulp, wood pulp or the like, the combination of a press, a 40 lower mold part adapted to contain pulp and fitted to the press, a movable upper mold part detached from the press normally mounted above the lower mold part and adapted to coöperate therewith, a suction 45 box attached to the upper mold part, a series of ducts in the suction box communi-

cating with an exhausting device and the upper mold part, means for pressing said mold parts together to form a sheet, and means whereby the sheet and the upper mold 50 part may be moved from above the lower mold part to a position external to the press.

3. In apparatus for the manufacture of thick large sheets of paper pulp, wood pulp or the like the combination of a press, a 55 lower mold part adapted to contain pulp and fitted to the press, a movable upper mold part detached from the press normally mounted above the lower mold part and adapted to coöperate therewith, a suction 60 box attached to the upper mold part, a series of ducts in the suction box communicating with the suction box, with an exhausting device, and with a source of compressed air, means for pressing said mold 65 parts together to form a sheet, and means for removing both the sheet from between the said mold parts and the upper mold parts to a position external to the press.

4. In apparatus for the manufacture of 70 thick large sheets of paper pulp, wood pulp or the like, the combination of a press, a track fixed to, located within and projecting externally and laterally of the press, a lower mold part containing pulp and fitted 75 to the press, an upper mold part movably mounted on the track and adapted to coöperate with the lower mold part, a suction box attached to the upper mold part, means for pressing said mold parts together to 80 form a sheet, and means for removing said sheet from between the mold parts to a position exterior to the press.

In testimony whereof we have signed our names to this specification in the presence of 85 two subscribing witnesses.

DANIEL MANSON SUTHERLAND,
DANIEL MANSON SUTHERLAND, JR.
